WITNESS

UNITED STATES PATENT OFFICE.

ALFRED V. RAPP, OF AKRON, OHIO.

FIGURE TOY.

Application filed November 17, 1923. Serial No. 675,838.

To all whom it may concern:

Be it known that I, ALFRED V. RAPP, a citizen of the United States, residing at Akron, in the county of Summit and State 5 of Ohio, have invented new and useful Improvements in Figure Toys, of which the following is a specification.

One object of my present invention is the provision of a toy of simple and inexpensive 10 construction adapted when put in motion on a supporting surface to afford considerable amusement to a child.

Another object of the invention is the provision of a toy that is so inexpensive in 15 construction that it is feasible to use it as an advertising novelty for gratuitous distribution.

To the attainment of the foregoing, the invention consists in the improvement as 20 hereinafter described and definitely claimed.

In the accompanying drawings, forming part of this specification:—

Figure 1 is a front elevation of my novel 25 toy, showing the preferred embodiment of my invention.

Figure 2 is a rear elevation of the toy.

Figure 3 is an edge elevation of the toy.

Figure 4 is an elevation of the oscillatory 30 element per se.

Figure 5 is a top plan view of the toy.

Similar numerals of reference designate 35 corresponding parts in all of the views of the drawings.

Among other elements my novel toy 40 comprises a circular base 1 of sufficient thickness to enable it to stand on a surface designated by 2. The said base 1 may be and preferably is in the form of a hollow box, and may be made of paper or any other 45 material compatible with its purpose. In the upper portion of the base 1 and at opposite sides of the vertical median line thereof are provided slots 3.

In addition to the base 1 my novel toy 45 comprises a figure body 4. The said figure body is formed of a piece of sufficiently stiff cardboard, the said piece of cardboard being punched out of a sheet so as to define a figure, preferably a grotesque figure, and 50 the front and back being provided by folding the figure body along the top edge 5, and the front or front wall being provided with eye openings 6 punched therein, and the fold being provided with a slot 7 also 55 punched therein.

The toy also comprises an oscillatory

member 8 which is punched or otherwise produced from a sheet of sufficiently stiff cardboard and preferably in a shape to 60 simulate arms as designated by 9 and also to simulate a tassel 10. It will further be noted that the member 8 is provided with dots 11 to simulate eye balls and is also embellished to simulate hands 12 on the arms 9. The said member 8 is interposed flatwise between the front and back walls of 65 the figure body 4 and so that the shank 13 adjacent to the tassel 10 extends through and is adapted to move in the before mentioned slot 7 in the fold 5. At 14 the member 8 is pivotally connected to the front and back walls of the figure body 4, and this pivotal connection may be effected by a pin, a piece of wire or any other available means.

The figure body 4 alluded to is shown as 70 provided with legs 15, and at the lower ends of these legs are tabs 16 which are seated in the slots 3 of the base 1 so as to join the figure body 4 to the base.

It will be manifest from the foregoing 75 that my novel toy is susceptible of being easily and inexpensively produced.

In the practical use of the novel toy, the 80 toy is rocked on its circular base 1 whereupon the vertical oscillation of the arms 9 and the rolling of the eyes 11 of the member 8 relative to the figure body 4 and the eye openings 6 therein will impart to the toy 85 a grotesque appearance calculated to afford amusement to a child and also calculated to attract the attention of adults, the latter being advantageous, of course, when the toy 90 is used for advertising purposes.

I have entered into a detailed description 95 of the construction and relative arrangement of the parts embraced in the present and preferred embodiment of my invention in order to impart a full, clear and exact understanding of the said embodiment. I do not desire, however, to be understood as 100 confining myself to the specific construction and relative arrangement of parts inasmuch as in the future practice of the invention various changes and modifications may be made such as fall within the scope of 105 my invention as defined in my appended claims.

Having described my invention, what I 110 claim and desire to secure by Letters Patent is:—

1. A toy comprising a circular base of a

- thickness to stand of itself and having slots in its upper portion at opposite sides of its vertical median line, a figure body having tabs socketed in the said slots of the base 5 and also having front and back walls and eye openings in its front wall, and an oscillatory member pivoted between the front and back walls of the figure body and having arms extending laterally from said body and 10 also having eye simulations arranged to be exposed by said eye openings and also arranged to move relative to said eye openings to impart a grotesque appearance to the toy when the same is rocked on its base. 15 2. A toy comprising a circular base of a thickness to stand of itself and having slots in its upper portion at opposite sides of its vertical median line, a figure body having tabs socketed in the said slots of the base and 20 also having front and back walls and eye openings in its front wall, and an oscillatory member pivoted between the front and back walls of the figure body and having arms extending laterally from said body and also 25 having eye simulations arranged to be exposed by said eye openings and also arranged to move relative to said eye openings to impart a grotesque appearance to the toy when the same is rocked on its base, the 30 said figure body also having a slot in its upper end, and the oscillatory member having a portion extending through said slot and movable therein and also extending beyond the upper end of the figure body. 35 3. A toy comprising a circular base of a thickness to stand of itself, a figure body superimposed on and joined to the base and having eye openings, and an oscillatory

member pivotally connected to the figure body and hidden in part by the same and having arms and also having eye representations arranged to be exposed by the said eye openings and also arranged to move relative to said eye openings. 40

4. A toy comprising a circular base, a figure body superimposed on and joined to said base and having front and back walls and also having openings, two of said openings being located to simulate eyes, and an oscillatory member pivoted between the front and back walls of the figure body and having arms extending laterally from the figure body and also having eye representations arranged to be exposed through the eye openings and to move relative to said openings. 45

5. A toy comprising a circular base, a figure body superimposed on and joined to said base and having front and back walls and also having openings, two of said openings 50 being located to simulate eye openings, and an oscillatory member pivoted between the front and back walls of the figure body and having arms extending laterally from the figure body and also having eye representations arranged to be exposed through the eye openings and to move relative to said openings; the figure body further having a slot in its upper end, and the oscillatory member being further provided with an upwardly extending extension disposed and movable in said top opening of the figure body. 55

In testimony whereof I affix my signature.

ALFRED V. RAPP.
